UNITED STATES PATENT OFFICE.

FRANK H. VAN HOUTEN, JR., OF FISHKILL-ON-THE-HUDSON, NEW YORK.

INTERNAL-COMBUSTION ENGINE.

1,133,896.

Specification of Letters Patent. Patented Mar. 30, 1915.

Application filed May 29, 1914. Serial No. 841,875.

To all whom it may concern:

Be it known that I, FRANK H. VAN HOUTEN, Jr., a citizen of the United States, residing at Fishkill-on-the-Hudson, in the county of Dutchess and State of New York, have invented certain new and useful Improvements in Internal-Combustion Engines; and I do hereby declare the following to be a full, clear, and exact description of the same, reference being had to the accompanying drawing, forming part of this specification, and to the figures and letters of reference marked thereon.

This invention relates to internal combustion engines, the objects being to provide a light weight engine having a maximum power with a compact arrangement and an engine which, while operating to give a power impulse on the piston during each stroke, will effectually discharge the previously ignited charge before the admission of a new charge.

The invention contemplates an engine in which the ignited or exploded charge will be driven out of the working chamber of the cylinder by the rearward movement of the piston and a new charge forced into the working chamber under an initial compression which substantially corresponds to the pressure ordinarily created by the compression stroke of the piston in the usual four-stroke cycle engine.

The engine of the present invention preferably embodies in its construction features which are customarily employed in both the four and two-stroke cycle types of engine; that is to say, the inlet and exhaust ports of the working chamber of the cylinder are valve-controlled ports, and in addition the piston controls ports for the intake of the fuel charge and the compression and transfer of the fuel charge to the working chamber of the cylinder, the construction lending itself most favorably to that type of engine known as the opposed cylinder type.

Referring to the accompanying drawings,—Figure 1 is a sectional plan view of an engine embodying the present improvements; and Fig. 2 is a section through the engine in a vertical longitudinal plane through the center of the cylinders.

Like letters of reference in both figures indicate the same parts.

In illustrating the engine of the present invention, it has been deemed unnecessary

to show certain conventional features which are well understood in the art and which may be varied in accordance with preferred or approved practice; thus, for example, the cylinders of the engine illustrated are shown without external cooling means, and it will be understood that either the ordinary water jacketing may be employed or radiating fins, ribs, etc., should it be desired that the engine be of the air-cooled type.

In said drawings, the letter A indicates the opposed cylinders which are preferably arranged in axial alinement and of uniform diameter throughout. Each cylinder is provided at its outer end with a head B preferably forming the charge receiving chamber of the working chamber of the cylinder. Communicating with the charge receiving chamber in the head of each cylinder is an exhaust port C controlled by a valve c adapted to be operated by a valve cam D rotated from the crank shaft, as will be presently described. Each cylinder head is also provided with an inlet port E preferably controlled by a spring seated puppet valve e, it being understood, of course, that both the valves c and e are of any ordinary or preferred type, such, for example, as the conical inwardly opening valves illustrated.

The piston F which is mounted to reciprocate in the cylinders is provided with an internal cylindrical chamber for each cylinder, each closed at its opposite ends by the walls of the piston, and as a convenient construction the central solid portion of the piston may constitute one end wall of the cylindrical chamber, and a head f at the other end wall, said head f, however, also constituting the face of the piston which is exposed to the working chamber of the cylinder. Each chamber is divided by an internal fixed piston G into compression and cooling chambers g and g' respectively, and the compression chambers g are each provided with a port H adapted to register alternately with a centrally arranged intake port I and with a transfer port K. The said ports I and K are preferably located in position for the port II to register therewith when the piston is at or approaching opposite extremes of its stroke. The intake port I is in communication with any suitable charge forming device, such, for example, as a carburetor, and the transfer ports K communicate through suitable transfer ducts k

with the inlet ports E for transferring the compressed charge from the compression chamber into the working chamber of the cylinder.

5 The fixed pistons G which divide the piston chambers into cooling and compression compartments are preferably mounted in fixed position on tubular supports M arranged axially of the cylinders and rigidly mounted at their outer ends in the cylinder heads, there being a suitable bearing in the piston heads f to permit of the reciprocation of the piston while maintaining a sufficiently tight bearing around the support to prevent 10 the escape of pressure during the working stroke of the piston.

With the construction described, it will be apparent to those skilled in the art, that the movement of the piston F in either direction 20 will tend to create a vacuum in one of the compression chambers and a corresponding compression of the charge in the other of the compression chambers. When the movable piston approaches the extreme of its movement, the chamber in which vacuum 25 conditions are produced is put into communication with the intake and receives a fuel charge which charge is compressed during the reverse movement of the piston, and as the piston approaches the extreme 30 of its movement in that direction the compression chamber is put into communication with the transfer passage and the compressed charge is transferred through 35 the valve controlled port into the working chamber of the cylinder, where it may be ignited by the ordinary igniting means, such as the spark plug O, to give an impulse for driving the piston in the opposite direction. 40 During the movement of the piston rearwardly the exhaust valve e is opened and the burned gases are driven out by the piston, so that the working chamber is practically cleared before the new charge is forced into 45 the same.

While the reciprocation of the piston may be converted into rotary mechanical movement through any known or preferred arrangement, it is conveniently accomplished 50 through a crank shaft P to which it is connected by a box p mounted to slide in a yoke Q rigidly connected with the piston, preferably at the center thereof, as shown in Fig. 2, said yoke being adapted to work in a 55 longitudinal slot R in the side wall of the intermediate portions of the cylinders.

The crank shaft P carries a fly wheel P', and is adapted to drive the valve cam D through a train of gear wheels p' indicated 60 in dotted lines in Fig. 2, the proportioning of the gears being such as to rotate the valve cam in time with the rotation of the crank shaft, for with the arrangement illustrated and described, it is designed that a power 65 impulse shall be imparted to the piston each

time it advances, or at every other stroke, and inasmuch as there is a cylinder with a working chamber at each end of the piston, two impulses will be imparted to the crank shaft during each revolution.

By making the support M for the fixed piston a tubular support, it may be conveniently utilized as the means whereby a cooling medium may be admitted into the internal chamber of the piston, so as to keep the 70 walls of the parts at a temperature best adapted for their economical operation. Any cooling medium desired may be utilized, but under ordinary conditions, it is found that by leaving the outer end of the 75 tubular support open to the air, fresh, cool air will be pumped into and out of the chambers by the reciprocation of the piston, and this air will carry off sufficient heat to maintain the temperature proper for ordinary 80 working conditions.

Having thus described my invention, what I claim as new and desire to secure by Letters Patent of the United States, is:

1. In an internal combustion engine, the 90 combination of the cylinder, piston mounted to reciprocate therein and having an internal cylindrical chamber, a fixed piston dividing said chamber into compression and cooling chambers, means for admitting cooling medium into said chamber on one side of the fixed piston, means for admitting a fuel charge into said chamber on the opposite side of the fixed piston, and means for transferring said charge under 95 pressure to the combustion chamber of the cylinder.

2. In an internal combustion engine, the 100 combination of the cylinder, piston mounted to reciprocate therein and having an internal cylindrical chamber having heads at its opposite ends, a fixed piston dividing said chamber into compression and cooling 105 chambers, means for admitting a fuel charge into said chamber on one side of said fixed piston and for transferring the compressed charge to the cylinder at one end of the reciprocating piston, and a support for the fixed piston extending through the wall of the movable piston having a 110 passage therein for the admission of a cooling medium to the cooling chamber.

3. In an internal combustion engine, the 115 combination of the cylinder, piston mounted to reciprocate therein and having an internal cylindrical chamber of greater length than the length of the piston stroke, a piston within and dividing said chamber into compression and cooling chambers, a tubular support for said last mentioned piston extending through the wall of the first mentioned piston and open to the chamber, means for admitting a fuel charge into said chamber on the compression side of the piston 120 therein and for transferring said charge 125 130

- to the cylinder at one end of the reciprocating piston, and means for igniting the charge so transferred.
4. In an internal combustion engine, the combination of the cylinder having an intake port and a transfer port and passage leading from a point between the intake port and end of the cylinder to the end of the cylinder, a piston mounted to reciprocate in the cylinder and having an internal cylindrical chamber with a port therein adapted to register alternately with the intake and transfer ports, a fixed piston in said chamber dividing the same into compression and cooling chambers, and a support for said piston having a duct therein communicating with the cooling chamber.
5. In an internal combustion engine, the combination with the cylinder having valve controlled inlet and exhaust ports at one end, an intake port near the opposite end, a transfer port at an intermediate point and a transfer duct connecting the transfer and valve controlled inlet ports, of a piston mounted to reciprocate in said cylinder and having a cylindrical chamber therein with
- 30 a port in position to register alternately with the intake and transfer ports, a fixed piston in said chamber dividing the same into compression and cooling chambers, and a tubular support for the fixed piston open at its inner end to the cooling chamber.
6. In an internal combustion engine, the combination with opposed duplicate cylinders having a common intake port at an intermediate point, and independent transfer ports and ducts leading to the outer ends of the cylinders, of connected pistons mounted to reciprocate in the cylinders, each piston having an internal cylindrical 40 chamber each provided with a port adapted to register with the inlet port and one of the transfer ports, a fixed piston in each chamber dividing the same into compression and cooling chambers, and means for admitting cooling medium to the cooling chambers when the piston reciprocates.
